THOMAS G. STANSBERRY, OF MEDORA, ILLINOIS.

Letters Patent No. 68,465, dated September 3, 1867.

IMPROVEMENT IN BELT-TIGHTENER.

The Schedule referred to in these Letters Patent and making part of the same.

TO ALL WHOM IT MAY CONCERN:

Be it known that I, THOMAS G. STANSBERRY, of Medora, in the county of Macoupin, and State of Illinois, have invented certain new and useful Improvements in Tightening Elevator-Belts; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention consists of a new and improved belt-tightener, by which elevator or other belts may be conveniently shortened and held in position while being laced or fastened. In the drawings—

Figure 1 is a top plan view.

Figure 2 is a sectional view on the line x x of fig. 1; and

Figure 3 is a detached sectional view on line x x of fig. 1, after the shaft has made half a turn.

I construct my belt-tightener of an iron shaft, B, of any convenient length and size, having a slot, a, in its centre, and provided with a crank, C, and ratchet-wheel, b. Through the slot a, I pass a leather strap A, and to each end of this strap attach a three-tined iron hook, D. These hooks I construct with an opening, c, in their heads, as shown in fig. 1. The shaft B, I mount upon a frame, E, and provide it with bearings at d and e. To this frame I attach a pawl, which plays into the ratchet-wheel b.

In operating or using my belt-tightener, I adjust the hooks D into the upper and lower ends of the elevator or other belt sought to be tightened, as shown in fig. 2, then turn the crank C, which causes the strap A to wind up on the shaft B, as shown in figs. 2 and 3; and the hooks D to approach each other and draw the ends or portions of the belt to which they are attached together. When thus drawn up, the ratchet and pawl keep the shaft in whatever position it is placed. The elevator or other belt which is being tightened can then be laced or fastened through the openings c, if necessary.

It will readily be seen that the ratchet-wheel and pawl may be made so that, by holding up the pawl, the crank may be turned in either direction, and when it is desired to hold the shaft in any desired position, the pawl can be dropped into the ratchet-wheel, or when using my belt-tightener to tighten elevator belts, a pawl can be fastened on to the side of the elevator frame, to be used in connection with the ratchet-wheel.

Having thus described my invention, what I claim, is—

The slotted shaft B, provided with a crank and ratchet-wheel, in combination with the strap A, having tined hooks at its ends, arranged to operate substantially as shown and described.
